UNITED STATES PATENT OFFICE.

WILLIAM E. SHEEHY, OF EAST BOSTON, MASSACHUSETTS.

SHOE-POLISHER.

1,351,136.

Specification of Letters Patent. Patented Aug. 31, 1920.

Application filed September 5, 1919. Serial No. 321,868.

To all whom it may concern:

Be it known that I, WILLIAM E. SHEEHY, a citizen of the United States, and resident of East Boston, county of Suffolk, State of Massachusetts, have invented an Improvement in Shoe-Polishers, of which the following description, in connection with the accompanying drawing, is a specification, like characters on the drawing representing like parts.

This invention relates to improvements in shoe polishers and the object thereof is to provide a shoe polisher which will be simple in construction and more effective in operation than those heretofore produced.

One of the objects of the invention is to provide a shoe polisher having means for guiding a flexible shoe polishing instrumentality such as a strip of felt or other textile fabric so disposed as to cause the fabric when reciprocated to have a tendency to creep toward the heel of the shoe and thereby prevent the same from working off of the toe of the shoe as is usual in polishing machines of this type.

Another object of the invention is to provide a rigid construction in which the support for the shoe will be reinforced throughout its length.

Other objects and features of the invention will more fully appear from the following description and accompanying drawings and will be pointed out in the annexed claims.

A preferred embodiment of my invention is illustrated in the accompanying drawings in which,

Figure 1 is a plan view,

Fig. 2 is a side elevation,

Fig. 3 is an end elevation, and,

Fig. 4 is a vertical sectional view on lines 4-4, Fig. 3.

The polishing device illustrated in the accompanying drawing comprises a base 1 preferably in the form of a metal plate to which a shoe supporting member is secured. The shoe supporting member desirably comprises a plate 2 having vertical ends 3, 4 provided with flanges 5, 6 secured to the plate 1 by suitable rivets 7 or other fastenings.

The plate 2 desirably is provided with downwardly extending marginal strengthening flanges thereby enabling the use of relatively light material. The surface of the plate 2 desirably is inclined upwardly

from the heel supporting portion to the toe supporting portion and may be slightly concaved to conform to the surface of the bottom of the shoe.

Guides 8, 9 for a flexible polisher 10, such as a strip of felt or the like, are secured to the ends 3, 4 of the shoe support, these guides may be of any desirable form but preferably comprise rollers mounted upon rods 11, 12 anchored in the vertical plate 3 at the heel portion of the support.

The opposite ends of the rods 11, 12 may be supported by the vertical end 4 of the support in any desirable manner. As illustrated herein the vertical end 4 is provided with a groove 13 which may be stamped in the plate during its formation, and which is adapted to receive a rod 15 having at its ends bosses 16, 17 apertured to receive the ends of the rods 11, 12, the rods being screw threaded and secured thereon by suitable nuts 18.

The guides 8, 9 desirably diverge from the heel portion of the shoe support toward the toe portion so that at the toe portion they are spaced apart a considerable distance wider than the toe portion of the shoe while at the rear portion their outer surfaces are substantially a distance apart equal to the width of the heel of a shoe.

A single roller may be mounted upon each of the rods 11 and 12 but preferably two or more rollers are placed upon each rod for convenience in manufacturing and assembling.

The rollers desirably are made of wood and provided at their ends with bushings 19 to prevent the wearing away of the wood as the rollers are rotated during the operation of the device.

In operation the flexible polisher is carried beneath the rollers and the portion intermediate of the rollers upwardly over the top of the shoe. The operator then grasps the ends of the polisher and pulls first with one hand and then with the other, thereby reciprocating the portion which passes over the shoe back and forth with as much pressure as desired.

By reason of the divergence of the guides the polisher may be carried over a single guide and reciprocated to polish the instep portion and heel of the shoe.

It will be understood that the embodiment of the invention disclosed herein is illustrative and not restrictive and that it may be

modified within the meaning and scope of the following claim.

Having thus described my invention what I claim as new and desire to secure by Letters Patent is—

A polishing device comprising a base, a plate having vertical end portions provided with flanges secured to said base and an intermediate shoe supporting portion, the

vertical portion at the toe end having a transverse groove therein, shafts, having guiding rollers thereon, anchored at one end in the vertical heel portion and means seated in said groove supporting the other ends of said shafts.

In testimony whereof, I have signed my name to this specification.

WILLIAM E. SHEEHY.
